UNITED STATES PATENT OFFICE.

WILLIAM WILSON, OF BLOOMINGTON, ILLINOIS.

SPARK-ARRESTER.

SPECIFICATION forming part of Letters Patent No. 361,738, dated April 26, 1887.

Application filed November 23, 1886. Serial No. 219,720. (No model.)

To all whom it may concern:

Be it known that I, WILLIAM WILSON, residing at Bloomington, in the county of McLean and State of Illinois, and a citizen of the 5 United States, have invented a new and useful Improvement in Spark-Arresters, of which the following is a full description, reference being had to the accompanying drawings, in which—

Figure 1 is a vertical longitudinal section. 10 Fig. 2 is a horizontal section, the right-hand portion of this figure being a section at line *x* of Fig. 1, and the left-hand portion being a section at line *y* of Fig. 1, the smoke-arch, flues, exhaust-pipes, and some other parts being omitted for the purpose of clearly showing the 15 spark-box and some other parts. Fig. 3 is a detail, being a section at line *y* of Fig. 2. Fig. 4 is a detail showing one of the valves which controls the passage which leads out from the 20 spark-box in section, showing the other corresponding valve in elevation. Fig. 5 is a section at line *x* of Fig. 4. Fig. 6 is a section through the spark-box at line *w* of Fig. 1, the cover of the spark-box being removed and the 25 operating-levers and the parts to the rear of the spark-box being omitted.

The object of this invention is to provide 30 more efficient means for preventing the escape of fire and sparks from the stack of a locomotive or other engine in which the escape of steam is utilized to create a draft, which I accomplish by providing a spark-box into which there is a communication from the smoke-arch controlled by a damper or valve, by providing 35 deflecting-plates to aid in guiding the sparks to the spark-box, by providing passageways from the spark-box back to the fire-box, and by providing for the admission of air to such passage, all as illustrated in the drawings, 40 and hereinafter fully described. Those things which I claim as new will be pointed out in the claims.

In the drawings, A represents the fire-box of 45 a locomotive; B, the flues; C, the smoke-arch; D, an exhaust-pipe; E, a deflecting-plate in front of a portion of the flues; F, another dia- 50 phragm or deflecting plate, which is in effect a continuation of the top of the spark-box, terminating at its upper end near the longitudinal center of the smoke-arch and its upper end being at or near the top of the exhaust-pipes.

G is a spark-box, the rear wall of which is provided with an opening, *a*, through which sparks can pass from the smoke-arch to the 55 spark-box.

b is a damper or valve to control the passage *a*. This valve is located on a shaft *c*, supported in suitable bearings in the walls of the spark-box.

d is an arm or lever upon the shaft *c*. *e* is a rod pivoted to the upper end of the lever *d*, which rod extends back to the cab.

f g are two valves, one on each side of the spark-box, located upon a shaft, *v*, which is 65 supported in bearings in the sides of the spark-box.

h is an arm or lever secured at its upper end to the shaft *c*, upon which is the valve *b*.

i is a lever, the lower end of which is connected to the shaft *v*, on which the valve *f* is placed.

j is an arm or bar connecting the levers *h i*. The other end of the shaft *v* is provided with a lever corresponding with the lever *i*, the upper end of which is connected by an arm corresponding with *j* to the lower end of an arm or lever corresponding with *h*, which is connected with the shaft *c*.

H I are two passages leading from the spark-box back to a chamber, *J*, in front of the fire-box. The forward ends of these passages *H I* communicate with the spark-box, and the valves *f g* are each arranged in a casing or chamber provided with openings, which openings are controlled by the valves, and these chambers communicate with the forward ends of the passages *H I*.

K L are two pipes, one upon each side of the fire-box, the forward ends of which pipes communicate with the chamber *J*. The other ends of these pipes are closed.

k are hollow stay-bolts, the outer ends of which communicate, some with the chamber *J*, some with the tube *K*, and some with the tube *L*, by means of short pipes *l*, as shown in Fig. 3, or any other suitable manner.

m m are two pipes the outer ends of which are open to the air. These pipes pass through the spark-box, and their inner ends are open 100 and are located one in each of the passages *H I*, as shown in Fig. 1 and by dotted lines in Fig. 2.

o o are flanges on the top of the walls, which

extend upward from the plate which forms the bottom of the passage *a*.

p are flanges on the front and side walls of the spark-box. The top *q* of the spark-box is secured to these flanges.

M is a wire-netting, the lower end of which is closely connected to the exhaust-pipes and its upper end is closely fitted to the smoke-stack. The valves *b f g* can all be operated together, and are so arranged that when the valve *b*, which controls the passage from the smoke-arch to the spark-box, is closed, as shown in Fig. 1, the valves *f g* will be open, and when the valve *b* is open, so that sparks can pass from the smoke-arch to the spark-box, the valves *f g* will both be closed.

The operation is as follows: Suppose the valve *b* to be open and the valves *f g* to be closed, then sparks which pass through the flues will be deflected downward by the diaphragm or deflecting plate *E*, and, as they move very swiftly, they will be carried across through the smoke-arch and passage *a* into the spark-box *G*. The deflecting-plate *F* will have a beneficial effect in aiding to prevent the upward movement of the sparks after they pass the lower end of the deflector *E*. When the spark-box is full or nearly so, the engineer, through the rod *e*, can close the valve *b* and at the same time open the valves *f g*, and then communication between the smoke-arch and spark-box will be closed, and communication from the spark-box through the passages *H I* to the fire-box will be open. As often as the steam is exhausted air will be drawn through the flues from the fire-box, and at the same time air and the cinders in the spark-box will be drawn through the tubes *H I*, chamber *J*, tubes *K L*, and hollow stay-bolts *k* into the fire-box, to take the place of the air drawn therefrom by the action of the exhaust-steam. At the same time a current of air will pass through the pipes *m m* into the passages *H I*, and a strong current of air will pass through the passages *H I*, facilitating the withdrawal

of the cinders from the spark-box, and also furnishing pure air to the fire-box to promote combustion.

When the spark-box has been emptied, which can be done ordinarily in three or four minutes, the valves *f g* can be closed and the valve *b* be opened, when the operation will be repeated. The spark-box may have a capacity sufficient to hold, say, five or six bushels of cinders.

An opening may be provided in the bottom of the spark-box, through which cinders may be removed in case of any stoppage in the passages leading from the spark-box back to the fire-box. This opening, if provided, will of course be kept closed, except when opened for the purpose of removing cinders.

In Figs. 1 2, *r* is the bottom of the passage *a*.

What I claim as new, and desire to secure by Letters Patent, is—

1. In combination with the smoke-arch and fire-box of a locomotive, a spark-box, a passage from the smoke-arch to the spark-box, a valve or damper to control such passage, one or more passages from the spark-box to the fire-box, one or more valves to control such passage or passages, said valves operating substantially as shown, and a diaphragm-plate, *E*, in front of the flues, substantially as and for the purpose set forth.

2. In combination with the smoke-arch and fire-box of a locomotive, the diaphragms *E F* in the smoke-arch, an exhaust pipe or pipes, a wire-netting, *M*, between the exhaust-pipe and smoke-stack, a spark-box, a passage from the smoke-arch to the spark-box, one or more passages from the spark-box to the fire-box, valves or dampers to control all such passages, and one or more air-tubes, *m*, substantially as and for the purpose specified.

WILLIAM WILSON.
